W. A. AND S. WILSON.

STREET INDICATOR.

APPLICATION FILED AUG. 5, 1918.

1,316,470.

Patented Sept. 16, 1919.

UNITED STATES PATENT OFFICE.

WALTER ALEXANDER WILSON AND SYDNEY WILSON, OF VANCOUVER, BRITISH COLUMBIA, CANADA.

STREET-INDICATOR.

1,316,470.

Specification of Letters Patent. Patented Sept. 16, 1919.

Application filed August 5, 1918. Serial No. 248,405.

To all whom it may concern:

Be it known that we, WALTER ALEXANDER WILSON and SYDNEY WILSON, both subjects of the King of Great Britain, and both residents of the city of Vancouver, in the Province of British Columbia, Canada, have invented certain new and useful Improvements in Street-Indicators, of which the following is a specification.

10 Our invention relates to improvements in street indicators, and the object of our invention is to provide a device adapted for installations in street cars by means of which the names of streets past which the car 15 travels may be indicated in a simple manner to the passengers prior to the arrival of the car thereat, and which device is simple in construction and easy of operation. A further object is to devise a street indicator having 20 automatic stopping and spacing means whereby the movement of a band on which the street names are displayed is automatically controlled so that the minimum amount of attention on the part of the operator is 25 required.

We attain these objects by the construction illustrated in the accompanying drawings in which—

Figure 1 is a face view of the device.

30 Fig. 2 is a back view with cover removed.

Fig. 3 is a side view with side plate removed.

Fig. 4 is an enlarged detail plan view of the automatic spacing means.

35 Fig. 5 is a side elevation of Fig. 4.

Fig. 6 is an enlarged detail view of the insulated socket.

Similar figures of reference indicate similar parts throughout the several views.

40 The device consists of a casing 1, formed of any suitable material and of any preferred shape having on its front side a display opening 2. Rotatably mounted within the casing adjacent its upper and lower ends 45 are upper and lower rollers 3 and 4 respectively to which the ends of a ribbon 5 are secured and on which the ribbon may be wound by the rotation of the rollers, the rotation being effected by means of a suitably mounted shaft 6 provided with worms 7 and 8 adapted to mesh with worm gears 9 and 10 secured respectively to the shafts of the rollers 3 and 4, the shaft 6 being mounted for longitudinal movement so that the 55 worms 7 and 8 may be moved at will into or

out of gear with their respective gears 9 and 10, a suitably mounted manually operated lever 11 having one end in engagement with the shaft being provided for the purpose of moving the shaft when required.

60 12 and 13 indicate guide rollers for the ribbon, which passes between them and a spacing roller 14 rotatably mounted in proximity to the upper roller 3 and the circumference of which is equal to the depth of the 65 display opening 2. This roller 14 may be of any suitable material, but its ends, however, are metallic, such as being formed of brass disks 15 and 16, and in order that these disks may be adapted for electrical contact 70 with one another they are mounted directly on a metal shaft 17, or if it is preferred to insulate them from the shaft then connection is established by means of a wire 18, indicated by the dotted lines in Fig. 2, the wire 75 having its ends soldered to the disks and extending therebetween within the roller.

70 20 indicates a member disposed adjacent one end of the spacing roller 14 and fulcrumed at a suitable point on a pin 21, while 80 22 indicates a spring member extending between one end of the member 20 and a stationary pin 23, the purpose of the spring being to keep the points of the contact arms 85 24 and 25 with which the opposite end of the member 20 is provided bearing on the end of roller 14, as shown more particularly in Fig. 5. These contact arms are insulated from each other, arm 24 being bent at its point to bear on the end of the roller 14 and 90 arm 25 being provided on its free end with a ball shaped projection 26 adapted also to bear on the roller end and to engage at a predetermined point in the rotation of the roller a cup shaped socket 27 formed in a 95 vulcanite portion 28 set into the brass disk 15 which forms the end of the roller and flush with the face of the same. 29 indicates a contact member suitably secured at one end to the casing adjacent the disk 16 of 100 the roller 14 and formed so that its free end bears resiliently on the disk.

A small electric motor 30 for operating the worm shaft 6 is mounted on a base plate 31 and its shaft is belt-connected to the shaft 105 6 by means of suitable pulleys 32 and 33 and the belt 34.

The circuit wiring for operating the device is as shown in Fig. 2, the main supply wires being indicated by the numerals 35 110

and 36, these wires being led from any suitable source to the terminals 37 and 38, from which branch wires 39 and 40 are led to the contact member 29 and one of the motor terminals, the other motor terminal being connected by a wire 48 to the terminal 41 in connection with the handle 42 of a switch 43, this switch being also provided with terminals 44 and 45 to the right and left of the handle 42, from which terminals wires 46 and 47 are led to the contact arms 24 and 25 respectively.

Having thus indicated the principal parts of the invention its operation will now be described.

When it is desired to move the band or ribbon past the display opening 2 so as to bring into view the name of the next street the operator first moves the switch handle 42 to the right so that it makes contact with terminal 44 and then immediately throws it over to the left to make contact with terminal 45. Now, when the switch was moved to the right the circuit was completed through main wires 35, branch wire 39, member 29, spacing roller shaft 17 or wire 18, as the case may be, contact arm 24, wire 46, terminal 44, switch handle 42, wire 48, the motor terminal, wire 40 and main wire 36, and the motor was set in motion, thus rotating shaft 6 and all the rollers, including the spacing roller 14. On moving the switch handle to the left, the motor still continues to operate, but the current is now cut off from wire 44 and switched on to wire 45 and contact arm 25, the motor circuit still remaining completed. Forward the termination of a complete revolution of the roller 14, however, the end of arm 25 contacts with the vulcanite portion 28, thus automatically breaking the circuit and stopping the motor and on the completion of the revolution the ball shaped projection 26 enters the socket 27 and prevents further movement of the roller, and as the circumference of the roller is equal to the distance the ribbon travels at each movement it will be evident that the travel of the ribbon is thus automatically controlled without attention on the part of the operator, whose only care is to first move the switch handle first to the right and then to the left.

From the foregoing it will be seen that

we have devised a simple and practical street-indicating device. As changes could be made, however, in the construction mentioned, within the scope of the claims without departing from the spirit thereof, it is intended that all matter contained in the accompanying specification shall be interpreted as illustrative and not in a limiting sense.

What we claim as our invention is:—

1. In a street indicator, a casing having a display opening, a band bearing street names, mechanism for moving said band past the display opening, an electric motor for operating said mechanism, a band-operated roller having one end adapted to form an electric circuit terminal provided with an insulated portion, a pair of suitably supported fingers adapted to bear on the terminal end of the roller one in advance of the other each finger forming a circuit terminal, an electrical circuit in which said motor, said roller terminal and the rear finger terminal are disposed, a circuit in which said motor, said roller terminal and the advanced finger terminal are disposed, and a switch for the alternate control of said circuits.

2. In a street indicator, a casing having a display opening, a band bearing street names, mechanism for moving said band past the display opening, an electric motor for operating said mechanism, a band-operated roller having one end adapted to form an electric circuit terminal provided with an insulated part having a socket, a pair of suitably supported spring-pressed fingers adapted to bear on the terminal end of the roller one in advance of the other each finger forming a circuit terminal and the advanced finger having a projection adapted to coact with the said insulated socket, an electrical circuit in which said motor, said roller terminal and the rear finger are disposed, a circuit in which said motor, said roller terminal and the advanced finger are disposed, and a switch for the alternate control of the said circuits.

Dated at Vancouver, B. C., this 15th day of July, 1918.

WALTER ALEXANDER WILSON.
SYDNEY WILSON.
